(57) **CLAIM**

The ornamental design for a surgical drape, as shown and described.

DESCRIPTION

FIG. 1 is a top plan view of a surgical drape showing my new design, the remaining portion shown in broken lines is for illustrative purposes only, and forms no part of the claimed design;

FIG. 2 is a side elevational view thereof;

FIG. 3 is a top plan view of a surgical drape showing an alternative embodiment of my new design, the remaining portion shown in broken lines is for illustrative purposes only, and forms no part of the claimed design; and,
FIG. 4 is a side elevational view thereof.
